(57) **CLAIM**

The ornamental design for a lighting device assembly, as shown and described.

DESCRIPTION

FIG. 1 is a top, right side, front perspective view of a lighting device assembly according to the present disclosure.

FIG. 2 is a top view of the lighting device of FIG. 1; FIG. 3 is a bottom view of the lighting device of FIG. 1; FIG. 4 is a front view of the lighting device of FIG. 1; FIG. 5 is a back view of the lighting device of FIG. 1; FIG. 6 is a left side view of the lighting device of FIG. 1; and,

FIG. 7 is a right side view of the lighting device of FIG. 1. The broken lines in the Figures illustrate portions of the article that form no part of the claimed design.

1 Claim, 7 Drawing Sheets
